United States Patent Office

Des. 227,742
Patented July 17, 1973

227,742

FORM AND JOIST HANGER

Duane D. Logsdon, 1719 Canyon Road,
Fullerton, Calif. 92631

Filed Nov. 5, 1971, Ser. No. 196,250

Term of patent 14 years

Int. Cl. D8—08

U.S. Cl. D8—229

FIG. 1.

FIG. 2.

FIG. 3.

FIG. 4.

FIG. 5.

FIG. 6.

FIG. 1 is an isometric view of a form and joist hanger embodying the new design of my invention;
FIG. 2 is a top plan view thereof;
FIG. 3 is a side-elevational view thereof;
FIG. 4 is a bottom plan view thereof;
FIG. 5 is an end plan view thereof; and
FIG. 6 is another end plan view.

The side of the form and joist hanger illustrated which is not shown in the drawing is a mirror image of the side view thereof shown in FIG. 3.

I claim:

The ornamental design for a form and joist hanger, substantially as shown and described.
